UNITED STATES PATENT OFFICE.

FRANK A. BOYSEN, OF WEBSTER CITY, IOWA.

DESIGN FOR A MEMBERSHIP-CHAIN.

SPECIFICATION forming part of Design No. 31,063, dated June 27, 1899.

Application filed May 24, 1899, Serial No. 718,118. Term of patent 31 years.

To all whom it may concern:

Be it known that I, FRANK A. BOYSEN, a citizen of the United States, residing at Webster City, in the county of Hamilton and State of Iowa, have invented and produced a new and original Design for a Membership-Chain; and I do hereby declare the following to be a full, clear, and exact description of the same, reference being had to the accompanying drawing, forming a part hereof.

The accompanying drawing represents a chain made up of a series of links embodying my design.

The leading feature of my design consists of a chain made up of a plurality of links joined together by rings, substantially as represented in the drawing.

1 in the drawing represents a chain for use in societies or organizations and is designed 15 to stimulate and increase the membership, the idea being to attach links as new members join the society or organization. The chain 1 is composed of a series of links 2,

which are formed with receiving and retaining apertures 3 at each end, the said links 25 being joined by split rings 4. Each link is formed with an enlarged portion 6 for receiving a suitable monogram indicative of the society or organization in which the membership-chain is employed, and it is intended to 30 have printed on each link the name of each member and the time of joining and also any other printed matter, such as a verse of scripture or some insignia connected with the organization or society.

Having now described my invention, what I claim as new, and desire to secure by Letters Patent, is—

The design for a membership-chain substantially as herein shown and described.

In testimony whereof I hereunto affix my signature in presence of two witnesses.

FRANK A. BOYSEN.
